TEXTILE SPOOL

Rawson Atwood, New York, N. Y., assignor to
Decorated Metal Manufacturing Company, Inc.,
Brooklyn, N. Y., a corporation of New York

Application August 1, 1942, Serial No. 453,249

7 Claims. (Cl. 242—123)

This invention relates to improvements in textile spools.

It is an object of the invention to provide an improved end assembly structure for spools.

It is a further object of the invention to provide such improved end assembly in conjunction with hollow barreled spools of pasteboard and sheet metal construction.

With these and other objects which will appear in the following full description in mind, the invention consists in the combinations and arrangements of parts and details of construction which will now first be fully described in connection with the accompanying drawing, and then pointed out more particularly in the appended claims.

In the drawing:

Figure 1 is a view showing the parts of a spool embodying the invention in a preferred form, in central longitudinal section, and at an intermediate stage of assembly;

Figure 2 is a view similar to Figure 1 but showing the parts completely assembled and on a somewhat enlarged scale;

Figure 3 is a cross section taken on the line 3—3 of Figure 2;

Figure 4 is a cross section taken on the line 4—4 of Figure 2;

Figure 5 is a plan view of an end flange member prior to assembly;

Figure 6 is an enlarged, fragmentary detail view in central longitudinal section and is taken on the line 6—6 of Figure 4; and

Figure 7 is a side elevation of an end plug showing grooves formed therein in assembly.

Referring now to Figure 1, the spool of the invention may comprise a barrel structure like that of my previous Patent No. 2,250,564, granted July 29, 1941, including an outer barrel 1, which is a section of cylindrical pasteboard tubing, an inner steel reinforcing tube 2, shown as a split or open-seam tube, and cup shaped braces 3 which are driven into tube 2 so as to force the same outwardly against the pasteboard outer barrel 1. The metal tube 2 is provided with tabs 4 for attachment to the spool ends.

Each spool end includes, as shown, a body member 5, an anti-thread-trapping liner 6 therefor and a wooden plug member, 7 or 8, at the drive end and at the opposite end, respectively. The anti-thread-trapping liner and its method of application are fully described both in my patent above referred to and in my Patent No. 2,250,563, granted July 29, 1941. The

end construction including the liner is shown merely by way of completeness of illustration, such liner forming no part of the present invention. The body of each end member 5 is formed with apertures 9 adapted to receive the fastening tabs 4 and includes a cylindrical portion 10 adjacent the apertures 9 and which is adapted to fit into the metal tube 2, to which the end flange structure is fastened by turning over the tabs 4 into the position shown in Figure 2. The cylindrical portion 10 is further formed with an inwardly turned or contracted serrated edge 11 comprising inwardly extending teeth 12 which are separated by recesses 13. In the construction shown, the edge 11 is formed by forcing inwardly the edge of cylindrical wall 10 and cutting out the recesses 13 to form the teeth 12. While this construction is preferable in use, a slightly less expensive method of formation of the serrated edge 11 may be employed, consisting in merely stamping or drawing the cylindrical portion 10, without cutting the edge into the form shown, and utilizing the random breaks produced in the metal and the unbroken metal between the same as a serrated edge.

At each end of the spool is provided a wooden plug, 7 or 8, having a central bore 14 which may be utilized as a spindle bearing and the inner end of which is preferably flared as indicated at 15 so as to assist in guiding a spindle into the same. In the case of a drive end member means such as the transverse slot 16 may be provided to engage the lugs of the driving member. As will be understood, the slot or other means for engaging a driving member may take such form as is desired, so as to conform to a given type of drive member, the particular construction shown being adapted to use with a drive member having two lugs on the opposite sides of a spindle base. In any case the spindle bores are preferably made smaller than the openings in braces 3, so that a spindle will not be in contact with the braces.

The wooden plugs 7 and 8 are formed so as to have a driving fit in the cylindrical portions 10 of the end flanges with the result that, when they are driven in during assembly, the teeth 12 cut and press into the wood, forming grooves as shown in Figure 7 so that the end plug is splined to the end flange. The plug bodies will, of course, also be compressed slightly by the turned over ends of the tabs 4. This, however, will not interfere with the proper grooving of the plug and its proper relationship to the other parts to any

noticeable extent and results in the wooden plugs holding the tab ends firmly against the inner surface of the wall 10, increasing the security of the tab fastening.

While not necessary in the practice of the present invention according to its broader aspect, the tabs 4 will preferably be relatively wide, and will be turned over so that while they are convex at their base portions, they are concave at their tips and conform closely to the inner cylindrical walls of the portions 10 of the end flange members 5, while being substantially circular and being substantially on the edges of the apertures 9 along the arc where the concave tip joins the concave base. Such construction, as further described and claimed in my co-pending application, Serial No. 411,002, filed September 16, 1941, results in a maximum security of fastening, due to deformation of the metal which prevents opening the tabs by a mere bending action. This tab construction, while claimed per se in my application just referred to, is especially advantageous in conjunction with the plug construction of the present invention, the plugs 7 and 8 serving further to hold the tabs 4 against separation, and the deformation of the tabs into the form described permitting the use of the plugs 7 and 8 with a driving fit without the danger of breaking which may sometimes occur with a tab which has not been properly performed before driving the plug.

The various parts described, apart from the plugs 7 and 8, are conveniently formed by stamping and drawing operations, so as to produce a light weight and inexpensive spool. The construction while shown as applied to a bobbin having a drive end, may also be applied to a spool having no drive end, in which case the lower end plug 7 may assume the same form as the upper end plug 8. The construction is also applicable to single flanged or flangeless pins, such application involving merely suitable modification or reduction of the end flange members 5-6 into the desired form.

The end construction described has numerous advantages over those previously employed. The use of a large number of teeth 12 permits of using teeth which press into the wood only to a shallow depth so that it is practical to use an ungrooved cylindrical plug and to groove the same during assembly without producing, on the one hand, a construction in which the plug is not adequately held due to the use of only a few keying members or, on the other hand, risking splitting of the wood or inaccurate centering of the spindle bearing where relatively deep grooves are cut during assembly. The construction shown is also advantageous by comparison with arrangements in which a plug member is pre-formed with a keyway or keyways adapted to register with keying members within a barrel, as such constructions require working to unduly fine tolerances or will result in a construction without the proper tightness. The plug and grooving arrangement of the invention, however, has been found to cause no difficulty even when expansion or contraction of the wood due to humidity conditions occurs.

While there is no advantage in reducing the number of teeth or projections which engage the plug, it is to be understood that the number of these projections is not critical and that they

5 may be reduced in number where this is found desirable for manufacturing or other reasons. A sufficient number of projections distributed around the inside of a barrel should however be provided so as to avoid risk of the plug being 10 forced off-center during driving and to furnish the required holding strength for the particular class of service for which the spool is intended.

What is claimed is:

1. In a spool, and in combination, a tubular barrel comprising an outer pasteboard tube and an inner split-seam metal reinforcing tube, an end member comprising a cylindrical portion fitting within the said barrel and having an inwardly turned serrated edge, and a wooden end plug having a driven fit within said cylindrical portion and grooved by said serrated edge during driving into said cylindrical portion.

15 2. In a spool and in combination, a tubular barrel body, end tabs on said barrel body, a spool end having apertures in registry with the said tabs, the said tabs being turned over so as to extend into the said barrel, and an end plug fitting into said barrel and in driven engagement with the said tabs.

25 3. A spool according to claim 2, in which the said spool end comprises a tubular portion extending into the said barrel between the said plug and the inner surface of the said barrel body.

4. A spool according to claim 2, in which the 35 said tabs are relatively wide, have cylindrical base and tip portions, which are respectively convex and concave, and substantially coplanar bend portions between said base and tip portions conforming closely to the edges of the said apertures.

40 5. In a spool, and in combination, a tubular barrel, end tabs on said barrel, an end member comprising a cylindrical portion fitting within the said barrel and having an inwardly turned serrated edge and having apertures in registry with said tabs, the said tabs being turned over so as to extend into the said cylindrical portion, and a wooden end plug having a driven fit within said cylindrical portion and grooved by said serrated edge during driving into said cylindrical portion.

45 6. In a spool, and in combination, a tubular barrel of substantially uniform inside diameter adjacent an end, an end member comprising a sheet metal cylindrical portion fitting within the said barrel and having a plurality of inwardly projecting teeth spaced from said barrel end, and a wooden end plug having a driven fit within said cylindrical portion and grooved by said teeth during driving into said cylindrical portion, the said plug extending into the said barrel beyond the said cylindrical portion and being of substantially uniform diameter throughout its length within said barrel.

55 7. A spool according to claim 6, in which the said plug is formed with a central bore for a spindle bearing.

60 65 RAWSON ATWOOD.

Patent No. 2,359,603.

CERTIFICATE OF CORRECTION.

RAWSON ATWOOD.

October 3, 1944.

It is hereby certified that error appears in the printed specification of the above numbered patent requiring correction as follows: Page 2, first column, line 31, for the word "performed" read --preformed--; and that the said Letters Patent should be read with this correction therein that the same may conform to the record of the case in the Patent Office.

Signed and sealed this 28th day of November, A. D. 1944.

(Seal)

Leslie Frazer

Acting Commissioner of Patents.
